The ornamental design for a polishing pad, as shown and

described.

DESCRIPTION

See application file for complete search history.

FIG. 1 is a top plan view of a polishing pad, showing our new design;

(56) **References Cited**

FIG. 2 is a front elevational view thereof, the left side elevational view, right side elevational view, and rear elevational views each being a mirror image of the front view shown;

U.S. PATENT DOCUMENTS

FIG. 3 is a bottom plan view thereof;
